ARCH SUPPORTING SHOE

Filed March 25, 1927

FIG. 7.

Inventor
John Jones
by Robert W. Jenner
Attorney.

Patented July 23, 1929.

UNITED STATES PATENT OFFICE.

JOHN JONES, OF WILKES-BARRE, PENNSYLVANIA.

ARCH-SUPPORTING SHOE.

Application filed March 25, 1927. Serial No. 178,394.

This invention relates to foot wear having built-in means for supporting the arch of the human foot; and it consists of a shoe provided with arch supporting devices as herein-
5 after fully described and claimed.

In the drawings, Figure 1 is a side view of the lower part of a shoe, partially in longitudinal section, and having arch supporting devices according to this invention. Fig. 10 Fig. 2 is a plan view, from above, of the insole removed from the shoe. Fig. 3 is a plan view, from below, of the shoe with the outsole and portions of the granular filling removed. Fig. 4 is a plan view similar to Fig. 3 but 15 showing a modification. Fig. 5 is a cross-section through the insole and other portions, taken on the line 5-5 in Figs. 1 and 2. Fig. 6 is a similar cross-section, taken on the line 6-6 in Figs. 1 and 2. Fig. 7 is a side view of 20 one end portion of the packing piece.

The outsole 7, the heel 8, and the upper 9 of the shoe are of any approved form and construction. In order to support the arch of the foot a shank stiffener 10 of spring 25 metal or material is arranged longitudinally under the insole 12, and between it and the outsole. This shank stiffener 10 is secured directly to the insole by prongs 13 or other approved fastening devices, and it has a longitudinal rib 14 on its lower side, which is channel-shaped in cross-section.

The insole 12 is formed of leather or other suitable material, and it is provided with a concavo-convex projection 16 arranged in 35 front of the shank stiffener 10. The projection 16 projects upwardly, and is positioned so that it comes under the middle part of the transverse arch of the foot in the metatarsal area. The projection 16 may be either circular or elliptical, and sufficient space is left 40 between it and the inner edge of the insole in line with the big toe to accommodate the latter. The welt 20 is secured to the upper in any approved way, and the space under 45 the insole is filled in with packing material 21 which is preferably granular and of the approved sort. This granular packing material fills the hollow of the projection, and prevents the projection from being crushed 50 down when the shoe is worn for some length of time.

A packing piece 18 of leather, or other suitable packing material, is arranged under the inside side portion of the insole 12 and 55 the welt. The upper side of the packing piece 18 is flat, and bears on the welt and on

the granular packing material. The packing piece 18 is curved to conform to the curvature of the welt and insole, and it is of substantially uniform width and has tapering 60 ends. The underside of the packing piece is convex or beveled, so that the packing piece is substantially segment-shaped in cross-section. It is of the same thickness throughout, except at the tapering ends which are also 65 tapered in thickness. The packing piece is secured to the welt by adhesive material at one edge, and its other edge overlaps a portion of the granular packing material and the adjacent side portion of the shank stiffener. 70

When the metal shank stiffener has a rib 14 the edge of the packing piece extends to this rib, but the packing piece is not secured directly to the shank stiffener or to the 75 insole, but only to the welt. The front end of the packing piece is arranged a little in advance of the concavo-convex projection 16, and its front end portion partially overlaps the said projection. The rear end of the packing piece 18 preferably extends to the heel portion of the shoe. 80

In the modification shown in Fig. 4, the shank stiffener 10' is a plain shank stiffener without any longitudinal rib, and the packing 85 piece 18' extends partway over the projection 16, but its rear end portion does not extend longitudinally past the shank stiffener. The form of packing piece 18' is sometimes desirable, and it can be used with a ribbed shank or with a plain shank. The outsole is sewed to the welt over the packing piece 18, and this is sufficient to hold it securely in place, and is found to be more desirable, and to make a more satisfactory and a more flexible shoe than when the packing piece 18 is secured directly to the shank and insole with rivets or other fastening devices. 95

When the projection 16 is elliptical its major axis is preferably arranged diagonally 100 and crosswise of the longitudinal axis of the shoe, with its front portion at the inner side part of the insole.

What I claim is:

1. In an arch supporting shoe, an upper 105 provided with a welt, an insole secured to the upper and welt and provided with a concavo-convex projection at its metatarsal portion, granular packing under the insole and filling the concavity of the said projection, an 110 outsole, and a packing piece arranged under the inner side portions of the insole and welt

with its front end portion underlapping a portion of the said projection, said packing piece being substantially segment-shaped in cross-section and having tapering and beveled end portions and being secured at its outer edge directly to the outsole and welt with its inner side portion unsecured to the insole.

2. In an arch supporting shoe, an upper provided with a welt, an insole secured to the upper and welt, an outsole, and a packing piece arranged under the inner side portions

15 of the insole and welt with its front end portion underlapping a part of the metatarsal portion of the insole, said packing piece being substantially segment-shaped in cross-section and having tapering and beveled end portions and being secured at its outer edge directly to the outsole and welt with its inner portion unsecured to the insole.

20 In testimony whereof I have affixed my signature.

JOHN JONES.
